[57] CLAIM

The ornamental design for a storage rack, as shown and described.

DESCRIPTION

FIG. 1 is a perspective view of a storage rack showing my new design and compact disc cases represented by dashed lines are for illustrative purposes only and do not form any part of the claimed design;

FIG. 2 is a right side elevational view thereof, the left side view being a mirror image thereof;

FIG. 3 is a top plan view thereof;

FIG. 4 is a front elevational view thereof;

FIG. 5 is a rear elevational view thereof;

FIG. 6 is a perspective view of a second embodiment of the storage rack; and,

FIG. 7 is a perspective view of a third embodiment of the storage rack.

FIG. 1
